UNITED STATES PATENT OFFICE.

OLIVER N. HOWERTON, OF EAST PEORIA, AND ERNEST STARBUCK, OF PEORIA, ILLINOIS; SAID STARBUCK ASSIGNOR OF HIS ENTIRE RIGHT TO CHARLES S. HOVENDEN, OF PEORIA, ILLINOIS.

TOY.

1,412,015.

Specification of Letters Patent. Patented Apr. 4, 1922.

Application filed January 29, 1920. Serial No. 354,967.

To all whom it may concern:

Be it known that we, OLIVER N. HOWERTON and ERNEST STARBUCK, citizens of the United States, residing at East Peoria, county of Tazewell, State of Illinois, and Peoria, county of Peoria, State of Illinois, respectively, have invented certain new and useful Improvements in Toys; and we do hereby declare that the following is a full, clear, and exact description of the invention, which will enable others skilled in the art to which it appertains to make and use the same.

This invention is directed to toys as a class, having reference particularly to the representation of a mounted fowl, animal, or the like, so constructed and organized that when drawn along a floor or other surface said fowl or the like is made to apparently seize and swallow a bait attached to a cord or string by which the toy is pulled.

An object, therefore, is to so mount a body representing a fowl or animal upon a rolling support that a string or cord attached to said support, carrying a "bait", will be wound on such support when pulled upon so that said fowl or animal will approach and seize said bait.

Another object of the invention is to provide a rolling support upon which is mounted a body representing a fowl or animal, to which support is attached a string or cord carrying a "bait", the relation of the cord to the support, aided by the inertia of the latter, being such that said cord when pulled will be wrapped upon said support causing the device to be drawn toward said bait.

Still another object is to so organize a structure, including a rolling support, and a body mounted thereon, representing a duck, for example, that the continuous pull on a leading-string or cord wrapping upon said support will cause the duck to approach a "bait" attached to said cord or string and apparently swallow it, said structure being made to move at a rate of speed of travel faster than the hand that pulls said cord or string.

We are aware that it is not new to attach a cord to a rolling support to cause the wrapping of the same upon the latter and the movement of said support toward the end of the cord being pulled due to the inertia of

the support, but the novelty in our device lies in mounting the body of a duck, for example, preferably in miniature, upon the support, and a bait upon the cord so that in pulling upon the latter the bait will be approached and apparently swallowed in a realistic manner.

To the end that the invention may be fully understood we have provided the accompanying drawing forming part of this application it being understood that said drawing represents merely one form of the device suitable for illustrating the invention.

Figure 1 is a side elevation of a toy duck, in part section, showing the mechanism of our invention.

Figure 2 is a plan of the same with parts of the body of the toy broken away.

Figure 3 is a diagram showing two positions of the toy, and

Figures 4 and 5 are transverse sectional elevations of a rolling support and winding drum showing the manner of operation to take up a string or cord.

The body of the toy which in this instance as stated, takes the form of a duck is preferably made of two half portions, A, A' of pressed metal though other ways of producing it may of course be readily adopted. It is mounted upon a rolling support comprising spaced wheels B each having a trunnion or axle stub C on its outer surface extending through openings D in the sides of the body, and constitutes the axle of the said support. This structure includes a drum E between the wheels to which is secured one end of a string or cord F which extends along the inside of the neck of the duck through eyes at G, H, and, for example, between the upper and lower bills J and K respectively, said string or cord having attached thereto at L at some distance from the drum a kernel of corn, for example, or a representation thereof; as a "bait".

M is a pitman attached at one end to the lower bill K in suitable manner, the said bill being pivoted to the head of the duck substantially as shown. The pitman at its other end takes around a portion N of the rolling support arranged eccentrically to the axis of rotation thereof of the drum and wheels.

The weight of the body A, A' is practi-

cally balanced over the axis of the wheels, the string or cord serving to hold the said body free of the surface drawn over in pulling the toy forward.

5 When the cord is pulled the rolling support, which is preferably fairly heavy, being in fact the heaviest part of the toy, is rolled in the direction indicated by the dart in Figure 4. That is to say, the inertia of the 10 support together with the winding of the string or cord upon a smaller circumference than that of the wheels causes the said support to roll toward the hand pulling the string. The cord or string is thus wound 15 upon the drum E with the result that the duck approaches the "bait" which enters the bill. In one full rotation, see Figures 4 and 5, the length of the string or cord wound on the drum is much less than the distance 20 traveled by the wheels. Otherwise considered, in a study of Figure 3 it will be seen that the "bait" has been moved, in pulling the string, a much less distance than the distance traveled by the duck so that the latter 25 overtakes the bait. Of course the relative sizes of the wheels B and the drum is not important, being mere choice, but these determine the distance the duck must travel before it reaches the bait.

30 The whole purpose is that in drawing the duck some little distance, the "bait" on the string or cord is gradually reached and apparently swallowed. As the said bait is met by the eye H inside the bill, abruptly ended, 35 while the pull on the wheels is stopped while the body due to momentum tilts forward, Figure 3, dotted lines, giving the duck the quite realistic appearance of swallowing the bait. By properly shaping the wheels B 40 the duck, if desired, may be made to have a characteristic manner.

As the duck moves the lower bill K is made to open and shut due to the connection of the pitman therewith and with the 45 eccentric portion N but this movement in no way interferes with the entrance of the bait between the bill portions.

As the string or cord may wrap upon 50 itself the drum in effect may increase in diameter as the duck is drawn forward and therefore the farther the duck travels the faster will it approach the bait. It is not required that the cord be wound upon the drum by hand to operate the toy since, as 55 shown in Figures 4 and 5, but rather it is to be unwound each time for another operation.

I claim:

1. A toy comprising a rolling support including a winding-drum, a body representing a living organism mounted upon and carried by the support, a flexible member attached at one end to the drum arranged when pulled at its other end to wind upon 60 the said drum and extending from the same

through and out of the mouth of the represented organism, and a bait attached to said member caused to be drawn into said mouth in the wrapping of the cord upon said drum.

2. A toy comprising a body representative 70 of a living organism, a rolling support therefor journaled therein including a winding-drum, a cord attached at one end to the drum and extending to, through and outside the mouth of the represented organism, and a 75 bait carried by said cord outside said body, said cord when pulled at its free outer end winding upon the drum and drawing the body toward the bait, the bait entering said mouth. 80

3. A toy comprising a body representative of a living organism, a rolling support journaled in said body including a winding-drum having a shorter circumference than that of the support, a cord attached at one 85 end to the drum extending to and out through the mouth of the represented organism, and a bait carried on said cord at a point distant from the said end outside the body, the structure being organized whereby in pulling 90 the cord the drum will take up said cord at its bait end and cause the body to approach the bait at a rate of speed of travel greater than that of the travel of the cord and finally overtake and receive the bait into it. 95

4. A toy including in its construction a body simulating a fowl having a pivoted lower bill-portion, a rolling support upon which the body is mounted comprising a pair of spaced wheels and a drum and having a part arranged eccentrically to its axis of rotation, said drum being shorter in circumference than said wheels, a cord attached to the drum extending through the neck of the fowl and out through its bill, 100 a "bait" attached to the cord, and a pitman attached to and connected between said lower-bill portion and attached to the eccentrically arranged portion. 105

5. In a toy, in combination with a body 110 simulating a living organism, its mouth including a pivoted portion adapted to open and close, of a rolling support upon which the body is supported, a cord attached to the support extending to and out through the 115 said mouth, a "bait" carried by the cord outside the body, said cord when pulled adapted to be wound upon said support drawing the body toward the bait, and mechanism connected to and between the 120 support and the pivoted mouth portion adapted in the advance of the body to open the said mouth portion to permit the entrance of the bait into said mouth.

6. In a toy, a figure simulating a living 125 organism, a rolling support on which it is mounted, a cord attached to the support and extending out through the mouth of the represented organism and wound on the support on being pulled, and a "bait" on said 130

cord, the latter in winding drawing the "bait" toward and into the mouth of said represented organism.

7. In a toy, a figure simulating a living organism, a rolling support upon which it is mounted, a movable mouth portion for the represented organism operated by said rolling support, a cord attached to and adapted to be wound upon the support when pulled, 10 the same extending out through the mouth of said represented organism, and a bait at-

tached to and between the ends of the cord drawn into the mouth during the winding of said cord.

In testimony whereof we affix our signatures in presence of two witnesses.

OLIVER N. HOWERTON.
ERNEST STARBUCK.
